UNITED STATES PATENT OFFICE.

CHARLES DRABEK, OF CLEVELAND, OHIO.

SPRING SUSPENSION FOR VEHICLES.

1,119,937.

Specification of Letters Patent.

Patented Dec. 8, 1914.

Application filed December 9, 1913. Serial No. 805,535.

To all whom it may concern:

Be it known that I, CHARLES DRABEK, a citizen of the United States, and a resident of Cleveland, county of Cuyahoga, and State of Ohio, have invented a new and useful Improvement in Spring Suspension for Vehicles, of which the following is a specification, the principle of the invention being herein explained and the best mode 5 in which I have contemplated applying that principle, so as to distinguish it from other inventions.

The subject of the present invention is a spring suspension for vehicles, which is 10 designed to reduce to a minimum the shocks caused by road obstructions and to give an easy and comfortable suspension for the body of the vehicle. In the present types of vehicles, referring more particularly now to 15 automobiles, the springs are in many cases supplemented by various shock absorbing devices and it is necessary to supply such mechanism in addition to the regular springs in order to secure the easy riding 20 qualities so much desired. My invention, 25 on the other hand, secures this advantage without the aid of any auxiliary device, by first diminishing the travel transmitted from the axle, and then effectively cushioning 30 such movement.

To the accomplishment of these and related ends, said invention, then, consists of the means hereinafter fully described and particularly pointed out in the claims.

35 The annexed drawing and the following description set forth in detail certain mechanism embodying the invention, such disclosed means constituting, however, but one of various mechanical forms in which the 40 principle of the invention may be used.

In said annexed drawing:—Figure 1 is a side elevation of my invention; and Fig. 2 is a plan view of the same.

In Fig. 1 I show two fixed supporting 45 members or axles 1 mounted upon suitable wheels, such axles being, of course, parallel. To each of such axles are pivotally connected two spaced parallel frame members 3 which extend longitudinally of the 50 vehicle and terminate adjacent to the other of such axles. Two more of such frame members 3 are disposed between the first two, and are similarly attached to the other of the axles 1. Adjacent to the free ends 55 of said frame members there are mounted transverse members 6 which are spaced and

are parallel and are each connected to such frame members 3. Such transverse members are pivotally connected to said frame members and are flattened upon the upper surface adapting them to be rigidly connected to two longitudinally disposed members 7 which together with such transverse members, form a platform to which the body of the vehicle is designed to be attached. It 60 will be seen that the platform consisting of these four members is rigid, although it is pivotally supported at each corner upon one of said four frame members. Leaf springs 9 connect each of such transverse members 6 65 with the otherwise free end of the frame member 3 to which the transverse member is attached. The action of the present spring suspension will be readily seen from the foregoing description of the construction. 70 Upon one of the wheels 2 striking an obstruction, that end of the axle 1 to which it is attached is moved upwardly, this action raising the attached end of the frame member 5 a certain distance. The transverse 75 member 6 which is attached to the frame member that is moved is, of course, also moved but through a much shorter distance than the axle by reason of the relative proportions of the two parts of the frame member 80 on either side of the point of attachment of such transverse member. A resistance to 85 such movement of the frame member is supplied by the spring which connects the transverse member to the end of the frame member. In this way the road shocks are 90 distributed throughout the entire vehicle to some extent and are partially absorbed, thus preventing any annoying jars or shocks to the occupants of the vehicle as is the case 95 with any of the spring suspension systems which are now in general use. The use of a rigid platform for the purpose of supporting the body member prevents the latter from being racked by any of the severe 100 strains to which it is ordinarily subjected, and increases the life of the body and of the entire vehicle.

It is unnecessary to say that the shocks 105 resulting from the movement of the vehicle over an uneven roadway are, by this spring suspension, transmitted substantially equally to the various parts of the body which is one object of such a device. The shocks are first diminished and cushioned, however, and the 110 resultant movement given the body is very slight in proportion to the initial movement

of the axles. No spring suspension now in use secures the present distribution of shocks although it is possible to distribute them to some extent by means of the so-called "platform" springs, which are open to the serious objection that they permit the body to sway badly when taking curves.

Other modes of applying the principle of my invention may be employed instead of 10 the one explained, change being made as regards the mechanism herein disclosed, provided the means stated by any of the following claims or the equivalent of such stated means be employed.

15 I therefore particularly point out and distinctly claim as my invention:—

1. In a vehicle, the combination with two fixed supporting members, of two frame members each pivotally attached at one end 20 to one of said supporting members, two other frame members each pivotally attached at one end to the other of said supporting members, a transverse member connecting said two first-named frame members 25 25 to one of said supporting members, connecting said two last-named frame members, connections between said transverse members, and resilient means connecting each of said transverse members to the frame members 30 30 to which it is already attached said resilient means being attached to the ends of said frame members.

2. In a vehicle, the combination with two fixed supporting members, of two fixed 35 frame members each pivotally attached at one end to one of said supporting members, two other frame members each pivotally attached at one end to the other of said supporting members, a transverse member connecting said two first-named frame members 40 intermediate the ends of the same, a second transverse member connecting said two last-named frame members intermediate the ends of the same, rigid connections 45 between said transverse members, forming therewith a rigid platform, and resilient

means connecting each of said transverse members to the frame members to which it is already attached, said resilient means being attached to the ends of said frame members. 50

3. In a vehicle, the combination with two fixed supporting members, of two frame members each pivotally attached at one end to one of said supporting members, two other frame members each pivotally attached at one end to the other of said supporting members, a transverse member connecting said two first-named frame members intermediate the ends of the same, a second 60 transverse member connecting said two last-named frame members intermediate the ends of the same, two members connecting said transverse members and forming therewith a rigid platform, and resilient means 65 connecting each of said transverse members with the free ends of said frame members to which said transverse members are attached.

4. In a vehicle, the combination with two axles, of two parallel spaced frame members each pivotally attached at one end to one of said axles, two other parallel spaced frame members each pivotally attached at one end to the other of said axles, two parallel spaced transverse members, each attached to two of said frame members intermediate the ends of the latter, other parallel spaced members connecting said transverse members and forming therewith a platform adapted to receive a vehicle body, and resilient leaves extending from the ends of said transverse members to the otherwise free ends of said frame members to which said transverse members are attached. 70 75 80 85

Signed by me, this 6th day of December, 1913.

CHARLES DRABEK.
